(57) **CLAIM**

The ornamental design for the wearing edge attachment segment, as shown and described.

DESCRIPTION

FIG. 1 is a perspective view of the wearing edge attachment segment.

FIG. 2 is a front elevation view of the wearing edge attachment segment.

FIG. 3 is a back elevation view of the wearing edge attachment segment.

FIG. 4 is a left side elevation view of the wearing edge attachment segment.

FIG. 5 is a right side elevation view of the wearing edge attachment segment.

FIG. 6 is a top view of the wearing edge attachment segment.

FIG. 7 is a bottom view of the wearing edge attachment segment.

In accordance with a second embodiment of the present design,

FIG. 8 is a perspective view of the wearing edge attachment segment.

FIG. 9 is a front elevation view of the wearing edge attachment segment.

FIG. 10 is a back elevation view of the wearing edge attachment segment.

FIG. 11 is a left side elevation view of the wearing edge attachment segment.

FIG. 12 is a right side elevation view of the wearing edge attachment segment.

FIG. 13 is a bottom view of the wearing edge attachment segment; and,

FIG. 14 is a top view of the wearing edge attachment segment.

1 Claim, 8 Drawing Sheets
